UNITED STATES PATENT OFFICE.

ISAAC J. TREMELLS, OF MOORETOWN, ONTARIO, CANADA.

INTERNAL-COMBUSTION ENGINE.

Application filed March 26, 1919. Serial No. 285,371.

To all whom it may concern:

Be it known that I, ISAAC JOHN TREMELLS, a citizen of the Dominion of Canada, and resident of Mooretown, Lambton County, Province of Ontario, Dominion of Canada, have invented new and useful Improvements in Internal-Combustion Engines, of which the following is a specification.

The invention relates to internal combustion engines but primarily to those of the two-stroke cycle type.

The object of the invention is to secure increased power and dependability of action with a minimum of complication, number 15 of working parts, friction and fuel expenditure.

It has been discovered that immediately following the outrushing of the exhaust gases, before the closing of the exhaust port, and prior to the admission of the new charge, a partial vacuum exists in the cylinder of internal combustion engines. This may be caused by the inertia of the exhaust gases travelling through the exhaust port at 20 a high velocity even after the pressure in the cylinder drops to the pressure of the atmosphere, or it may be caused in part by the sudden drop in temperature due to contact with the outside air at the exhaust port. 25 Others have utilized this partial vacuum assisted by fans and flues to draw in fuel and air before the exhaust port is closed.

When an explosive mixture is inducted in the ordinary two-stroke cycle engine while 30 the exhaust port is open, more of the explosive mixture is wasted than is converted into power. It escapes through the exhaust port.

In the present invention this partial 35 vacuum is utilized by first closing the exhaust valve before the charge of air and gas forming the explosive mixture is drawn in, the evaporation of the gas after it has entered the chamber taking up the heat to 45 lower the temperature of the explosion chamber, thereby increasing the speed with which the incoming gas will be inducted.

In the accompanying drawings,

Figure 1 is a vertical sectional view 50 through the cylinder of my engine, showing the piston at substantially the end of the exhaust portion of the stroke;

Fig. 2 is a fragmentary section of the upper portion of the cylinder showing a 55 modified form of valve, and

Figs. 3, 4, 5 and 6 are diagrammatic views

illustrating the position of the cylinder and valves at various stages in the cycle.

The cylinder 1 is shown as provided with the usual water jacket 2 and has formed in 60 its head fuel intake and exhaust ports, within which are seated valves 3 and 4.

The valve 4 is operated by means of the usual rocker arm 5 controlled through a valve rod 6 by the cam 7 mounted upon the 65 crank shaft 8. The valve 3 may be controlled by a similar rocker arm 9, rod 10 and cam 11, as shown in Fig. 1, or as shown in Fig. 2, the intake valve 12 may be of the ordinary automatic puppet valve type controlled by the spring 13.

The fuel supplied through the valve 3 or 12, may be delivered from any desired form of carburetor or mixing device not shown.

As indicated in Fig. 3, the power stroke 75 extends from the uppermost position of the piston 14 to a distance equal to about two-thirds more or less of the total outward stroke of the piston. The exhaust valve 4 is then opened while the piston 14 moves 80 through about half of the remaining portion of the outward stroke; the burning gases rush out. The exhaust valve 4 is then closed and the fuel inlet valve 3 is immediately opened. This inlet valve remains open 85 while the piston moves to the limit of its outward stroke and for a portion of the beginning of the upward or compression stroke of the piston until the pressure within the cylinder is substantially equal to the 90 atmospheric pressure. The intake valve is then closed and the remainder of the upward stroke compresses the fuel charge.

When the piston reaches the upper limit 95 of its movement, or slightly before the upward point is reached, the charge is ignited and the cycle is repeated.

It will be seen that the piston has reached substantially the effective end of its power stroke before the exhaust port is opened, and by the selection of the proper cam, the 100 position of the beginning and end of the exhaust period may be regulated to suit conditions to obtain the most efficient operation of the engine.

This engine when using an ordinary mixer without heating pipes, will burn coal-oil, distillate, and even crude oil. I have run the engine with equal parts of coal-oil, gasoline, and gas engine oil. My tests have established the fact that either liquids or gases 110 may be inducted into the explosion cham-

ber at or near the cylinder head without the use of a force pump or of a crank case compression, or other auxiliary devices.

The vacuum produced in the cylinder at 5 the end of the exhaust period is amply sufficient to produce the necessary induction of a new fuel charge during the short movement of the piston from the end of the exhaust portion of its stroke to a point at 10 which the piston has recommenced its movement of compression.

There is thus provided a two-stroke cycle engine in which the exhaust period may be adjusted in position and duration by a cam 15 having the necessary configuration and position upon the cam shaft and by which the position and duration of the intake period may also be adjusted by the provision of a similar cam upon the crank shaft.

20 I claim:—

In a two-stroke cycle internal combustion engine having a crank shaft, a cylinder, a piston in said cylinder adapted to revolve said crank shaft, said cylinder having an 25 upper end wall provided with fuel intake and exhaust ports, and mechanically operated valves movable to and from said cylinder ports for controlling the intake and exhaust of fuel and burned gases to and 30 from said cylinder:—means adapted to open

the exhaust port valve when said crank shaft has rotated approximately one hundred degrees of a revolution, said means maintaining said valve open during the following forty degrees of the revolution of said shaft, at the end of which partial revolution the exhaust valve is closed, and means to open the fuel intake port valve after the exhaust valve is closed, said means maintaining said intake port valve open during approximately one hundred degrees of further rotation of said shaft, said fuel intake port valve being maintained closed for approximately the remaining one hundred and twenty degrees of the revolution of said crank shaft, the timing of said intake and said exhaust port valve being such that a partial vacuum is produced in the cylinder so that at each opening of the intake valve there is a maximum induction of fuel.

In witness whereof I have signed the annexed application for Letters Patent. Signed at Winnipeg in the Province of Manitoba and Dominion of Canada this 21st day of March 1919.

ISAAC J. TREMELLS.
